UNITED STATES PATENT OFFICE.

MORRIS J. LYNCH, OF OTTAWA, KANSAS.

PRINTER'S COMPOSING-STICK.

No. 868,676.

Specification of Letters Patent.

Patented Oct. 22, 1907.

Application filed December 5, 1906. Serial No. 348,456.

To all whom it may concern:

Be it known that I, MORRIS J. LYNCH, a citizen of the United States of America, residing at Ottawa, in the county of Franklin and State of Kansas, have invented 5 new and useful Improvements in Printers' Composing-Sticks, of which the following is a specification.

This invention relates to printers' composing sticks, the object thereof being to provide a novel construction of composing stick especially designed for the use and 10 convenience of printers in assembling the various sizes and lengths of metal rule, border, leads, slugs, furniture or reglet to set same for any job or make-up, being especially adapted to save time in selecting the elements mentioned for use in composition work particularly 15 where the job or make-up is disposed at some distance from the cases containing the elements referred to.

The main object of the invention resides in the production of a composing stick which will admit of the convenient assemblage of the leads, etc. of any sizes or 20 lengths within determined measurements, and of their proper arrangement according to length or size, so that they may be readily and quickly removed for use as occasion requires.

A further object is to provide a composing stick 25 which is reversible to face in either direction, and may be employed as a gage or rule for measuring fillers of the type referred to or measuring any standard of type by the "point" system of type measurement.

The accompanying drawing shows a perspective view 30 of a composing stick embodying my invention.

Referring to the drawing, 1 designates the body of the stick, which comprises a strip of brass or any other suitable metal bent longitudinally along a medial line into L-form to provide assembling walls 2 and 3, arranged at 35 right angles to each other. Disposed at one end of the body is a preferably wooden handle 4 having a butt portion 5 fitting over upon the adjacent ends of the walls and secured thereto by suitable fastenings. The butt is preferably of polygonal form, or so shaped as to prevent 40 two sides lying at right angles to bear snugly against the walls 2 and 3. A plate 6 covers the inner end of the handle butt 5 and forms an end wall or abutment for the stick against which the rule, leads, slugs or other matter assembled therein may bear.

45 The stick as thus constructed is reversible so that it may be turned to face in either direction for the convenience of the compositor, and so that either wall 2 or 3 may serve as the base and the other as the back plate of the stick. The inner faces of both walls are provided 50 with sets of graduations having lines or indicating marks 7, 8 and 9. The lines 7 form a pica scale, which

range six to the inch, the scale preferably having a range of twelve inches or seventy-two lines pica. The lines 8 are shorter than the lines 7 and disposed between the same and constitute a nonpareil scale, measuring 55 up to 144 lines nonpareil. Each sixth line of the pica scale is extended to form the lines 9, which lines constitute inch divisions of an ordinary linear measurement foot rule. By this novel arrangement of the scale indications the leads, rule, etc., of any length up to and including 70 seventy-two pica lines or 144 nonpareil lines may be assembled in proper order for the convenience of the compositor, thus enabling him to quickly select the length or width of rule, border, slug or other spacing element for use in setting up the job. The elements 65 needed may, therefore, be stored in the stick at the point where the composition is being carried out, which may be a considerable distance from the rule and slug cases, thus effecting economy in time and labor in the operation.

The stick may also be used as a gage for measuring off rule, furniture and the like to be cut to suitable lengths, and for other general purposes.

Having thus described the invention, what is claimed as new, is:—

1. A printers' composing stick comprising a body having assembling walls coextensive in length and width and arranged at right angles to each other, said walls being provided with pica and nonpareil scales, and a handle having a butt portion fitting over upon and secured to the 80 walls at one end of the body and forming an abutment at that end.

2. A reversible printer's composing stick comprising an elongated sheet-metal strip bent into L-form to provide assembling walls coextensive in length and width, said walls being provided with graduations on corresponding lines forming pica and nonpareil scales, and a handle disposed at one end of the body and having a butt portion fitted over upon and secured to the adjacent walls, said handle having sides parallel to and bearing snugly against 90 said walls.

3. A reversible printer's composing stick comprising an elongated sheet-metal strip bent into L-form to provide assembling walls coextensive in length and width, said walls being provided with graduations on corresponding lines forming pica and nonpareil scales, a wooden handle disposed at one end of the body and having a butt portion fitted over upon and secured to the adjacent walls, said handle having sides parallel to and bearing snugly against said walls, and an abutment plate covering and secured to 100 the butt of the handle and bearing against said walls.

In testimony whereof I affix my signature in presence of two witnesses.

MORRIS J. LYNCH.
